(57) **ABSTRACT**

A launcher and projectile system include at least one permanent magnet disposed on or within the launcher for charging a wire coil of the projectile to energize an initiator of the projectile, thereafter having a housing of the projectile rupture, disintegrate, separate or otherwise have an opening created therein after launch to release a payload. In another embodiment, an accessory for a launcher and projectile is provided, the accessory comprising a permanent magnet for charging a projectile that is launched by the launcher.

CROSS-REFERENCE TO RELATED APPLICATIONS

The present disclosure is a continuation-in-part of and claims priority under 35 U.S.C. § 120 on pending U.S. Non-provisional application Ser. No. 17/319,295, filed on May 13, 2021, the disclosure of which is incorporated by reference.

tively large and heavy when compared to a projectile, and therefore limit the potential configurations of the projectile (due at least to the fact that the batteries occupy a substantial amount of space within the projectile). Furthermore, batteries are relatively expensive, thereby driving up the cost of manufacture of such a projectile. Furthermore, and quite concerningly, batteries drain and lose charge over time, which means that a projectile so configured may not be in a usable state for firing if it has been on the shelf for a length of time. This drawback is not acceptable, as the conditions under which such projectiles are to be used requires that they be ready to fire at all times.

Lethal projectiles have also been developed that fragment into multiple pieces, thus increasing the effective radius of such a projectile (and lowering the requisite targeting precision). Such fragmentation may be caused by components that are powered by a battery or batteries that is/are internal to the projectile or by the actual impact on the target. However, in that batteries are inherently respectively large and heavy when compared to a projectile, and therefore limit the potential configurations of the projectile (due at least to the fact that the batteries occupy a substantial amount of space within the projectile). Furthermore, batteries are relatively expensive, thereby driving up the cost of manufacture of such a projectile. Again, batteries drain and lose charge over time, which means that a projectile so configured may not be in a usable state for firing if it has been on the shelf for a length of time. This drawback is not acceptable, as the conditions under which such projectiles are to be used requires that they be ready to fire at all times.

All of the currently available methods for non-lethal projectiles suffer from one or more of the following disadvantages: difficult to target, not suitable for close range, not suitable for long range, inaccurate, sometimes lethal and often otherwise not effective, costly to manufacture, complex in configuration, and not reliably powered. Furthermore, with regard to lethal projectiles, most currently available methods drawbacks the requirement that such a projectile must impact the target to be effective and heavy and complex battery arrangements for power and operation.

FIELD OF THE DISCLOSURE

The present disclosure relates to non-lethal and lethal projectiles and related launching mechanisms and accessories and more specifically, to those projectiles with an initiator that may be activated during the launch phase of a launcher and/or a launcher accessory.

BACKGROUND OF THE DISCLOSURE

Non-lethal projectiles and non-lethal launching systems are commonly used by law enforcement for purposes of crowd control, such as quelling a riot or angry mob or to individually subdue a suspect. Increasingly, they may find usage as another means to augment self-defense in situations such as a home invasion, for example. The projectiles and systems (such as weapons that are capable of delivering such non-lethal projectiles) are designed to subdue a target subject or subjects for a time without causing permanent harm. Typically, such weapons systems require a projectile to burst on impact with the suspect and thus require accurate targeting and, in some cases, cause severe injury to a suspect. The most common means for such a device is a projectile that bursts on impact or a targeting device tethered by wires which delivers a high voltage shock thus immobilizing the suspect. All of these existing means suffer from a number of disadvantages outlined in more detail below.

The use of high voltage electric shock has been around for a number of years. While it is fairly effective at immobilizing a suspect, it suffers from the drawbacks that cardiac arrest in the target/suspect may result due to the voltage imparted into the suspect's body. Additionally, in the case of a suspect who is not in an open or unconstrained environment, such means requires accurate targeting to ensure that the electrodes contact the individual in order to deliver the electric shock. Furthermore, the longest effective range for such a device is less than 30 feet and more typically 10 or 15 feet. Additionally, the effectiveness of such weapons can be inhibited by clothing, coats or wet environments.

A second technique involves the use of a paintball that is filled with a *capsicum* or PAVA powder. While this eliminates or improves on the range issues of the electric shock techniques, it requires accurate targeting of the suspect. This is extremely difficult to do in short range as the ricochet of the powder off of a suspect can cause it to come back to the user. Furthermore, upon impact, the control of the powder release is not necessarily effective and can be one dimensional, meaning that it has difficulty stopping a suspect who is running away—as the cloud is left behind. Additionally, if the impact does not burst the projectile, the intended effect is not achieved.

Another approach is to provide for a projectile, the rupture or separation of which is caused by components that are powered by a battery or batteries that is/are internal to the projectile. However, in that batteries are inherently respec-

45 In view of the foregoing disadvantages inherent in the prior art, the general purpose of the present disclosure is to provide a projectile construction (also referred to herein as "projectile" in context), projectile launcher, and launcher accessory that include all the advantages of the prior art, and overcomes the drawbacks inherent therein. As used herein, "payload" may refer to a substance, object, compound, or material that is capable of delivering a lethal or incapacitating effect to and/or resulting in a lethal or incapacitating effect upon a target. Such a payload can be in powder, liquid or aerosol, or foam form and/or in the form of shrapnel (or a combination thereof) without departing from the spirit of the disclosure. The payload may comprise a debilitating material, a visible substance (such as a dye or a powder, for example) or an invisible marking substance (such as a UV-reactive material, for example) or a combination thereof.

In an embodiment, a launcher comprises at least one permanent magnet (hereinafter "magnet" as used throughout shall mean a permanent magnet unless particularly specified otherwise). The at least one magnet may be disposed within or in proximity to the barrel of the launcher, and in a further embodiment, proximate to the point of projectile exit, and in any event along the launch axis of the projectile. (See FIG.

1, for example). The at least one magnet is preferably magnetically-aligned with the launch axis. In an embodiment, the projectile comprises at least one coil of wire. When the projectile is launched, the at least one magnet of the launcher causes a rapid change in magnetic flux of coil of the moving projectile as it moves along the launch axis. This rapid change causes a current to be induced through the coil of the projectile, causing an inductive energy to be produced. In this way, it is understood that the at least one magnet of the launcher is capable of providing energy to the projectile. Those familiar in the art will recognize this as Faraday's Law of Induction

$$\left(\varepsilon = -N \frac{d\Phi_B}{dt} \right).$$

That is, electrical energy can be generated thereby from the change in magnetic flux as the projectile moves through the magnetic field caused by the at least one magnet of the launcher. As used herein, this inductive method may be referred to as "inductive activation" when it refers to activating a circuit and/or initiator of the projectile.

In another embodiment, an accessory for a launcher comprises at least one magnet. The accessory is configured to be removably attached to a launcher, and in an embodiment, to the barrel of a launcher. The at least one magnet of the accessory may be disposed within or in proximity to the barrel of the launcher, and along the launch axis of the projectile. (See FIG. 7, for example). The at least one magnet is preferably magnetically-aligned with the launch axis. As used herein, magnetic alignment comprises the creation of magnetic flux lines in the barrel or accessory such that a coil moving through the barrel or accessory receives an induced electrical charge. In an embodiment, the projectile comprises at least one coil of wire. When the projectile is launched, the at least one magnet of the launcher accessory causes a rapid change in magnetic flux of coil of the moving projectile as it moves along the launch axis. This rapid change causes a current to be induced through the coil of the projectile, causing an inductive energy to be produced. In this way, it is understood that the at least one magnet of the launcher accessory is capable of activating a circuit or an initiator of a projectile.

In an embodiment, the projectile separates into two or more components on exit from the barrel of a launcher to distribute a payload. In an embodiment, the separation can be initiated by electrical, mechanical or chemical means or by a combination thereof.

In another embodiment, an initiator may be disposed within the projectile. The initiator may either initiate a chemical reaction or otherwise cause a separation of the projectile through a mechanical or electromechanical method. The initiator and reaction can be initiated when current has been induced in the coil of wire of the projectile by the at least one magnet. In an embodiment, the initiator comprises an electric match, a nichrome wire coupled with a mechanical energy storage device (such as a spring), or a resistive heating filament. In an embodiment, the nichrome wire, when activated may cause the spring to expand to rupture the projectile.

In a still further embodiment in which the separation, opening, etc. of the projectiles is a result of a chemical reaction, an activating compound such as nitrocellulose may be initiated with the electric match, for example. The electric match may consist of a nichrome or similar high resistance

wire that is coated with a pyrogen. In an embodiment, wherein the launcher and/or launcher accessory comprises at least one magnet, when the projectile is launched, the at least one magnet of the launcher and/or accessory can activate the electric match by inductive activation.

DESCRIPTION OF THE DRAWINGS

The advantages and features of the present disclosure will 10 become better understood with reference to the following detailed description and claims taken in conjunction with the accompanying drawings, wherein like elements are identified with like symbols, and in which:

FIG. 1 is a longitudinal cross-sectional view of a projectile launcher 1000 with a projectile, according to an exemplary embodiment of the present disclosure.

FIG. 1A is a view of the barrel of a projectile launcher and at least one magnet of the launcher.

FIG. 2 are views of a projectile both before launch and 20 then during flight in which the housing of the projectile has separated and released a payload, in accordance with an exemplary embodiment of the present disclosure.

FIG. 3 is a view of a projectile launcher with a magazine, in accordance with an exemplary embodiment of the present 25 disclosure.

FIG. 4 is a view of a projectile comprising a payload and an initiator, in accordance with an exemplary embodiment of the present disclosure.

FIG. 5 shows a projectile with a ram, in accordance with 30 an exemplary embodiment of the present disclosure.

FIG. 6 shows a cross-sectional view of a projectile comprising a coil of conductive wire in accordance with an exemplary embodiment of the present disclosure.

FIG. 7 shows a projectile, launcher, launcher trigger and 35 a launcher accessory, the accessory comprising at least one magnet which magnetic field lines are shown in accordance with an exemplary embodiment of the present disclosure.

DETAILED DESCRIPTION OF THE 40 DISCLOSURE

The exemplary embodiments described herein detail for 45 illustrative purposes are subject to many variations in structure and design. It should be emphasized, however, that the present disclosure is not limited to a particular projectile or projectile launcher as shown and described. That is, it is understood that various omissions and substitutions of equivalents are contemplated as circumstances may suggest or render expedient, but these are intended to cover the 50 application or implementation without departing from the spirit or scope of the claims of the present disclosure. The terms "first," "second," and the like, herein do not denote any order, quantity, or importance, but rather are used to distinguish one element from another, and the terms "a" and "an" herein do not denote a limitation of quantity, but rather denote the presence of at least one of the referenced item.

The present disclosure provides for a projectile 100 and a launcher 1000, and, in an embodiment, a launcher accessory 1100. The projectile 100 preferably comprises a payload 200 for immobilizing and/or marking a target or suspect. It will be understood that payload as used herein may also comprise a substance, object, compound, or material that is capable of delivering a lethal or incapacitating force to and/or resulting in a lethal or incapacitating effect upon a 60 target.

The projectile 100 preferably comprises an enclosure, which enclosure may be formed by an at least partially

annular-shaped shell **102**. The shell may include a closed, substantially planar end portion **104** (also referred to herein as “end cap”) that corresponds to a radius of the annular portion of the shell to form the enclosure. The shell and end portion may individually and collectively refer to herein as a housing of projectile **100**. It will be apparent that the projectile housing is not limited to the shell and end portion configuration mentioned in the preceding exemplary embodiment, and that the projectile housing may comprise any shape that forms an enclosure without deviating from the spirit of the disclosure, such as, but not necessarily limited to a sphere or a cone. The payload **200** is preferably contained in the enclosure prior to launch of the projectile **100**.

In an embodiment, the projectile **100** is capable of self-separating, disintegrating or otherwise opening prior to impact with a target or other impact surface. In an embodiment, the launcher **1000** is capable of initiating separation or disintegration or rupturing or opening, etc. of the projectile **100**. In an embodiment, the launcher **1000** is capable of communicating to the projectile **100** and/or arming a projectile **100** prior to or coincident with projectile launch. In another embodiment, the launcher comprises a safety and/or trigger, which safety and/or trigger, until activated, prevent the projectile from becoming armed. The arming can be, for example, the activation of an initiator contained within the projectile.

In another embodiment and as shown in FIG. 1A, the launcher comprises at least one permanent magnet **500**. The at least one magnet **500** may be disposed within or in proximity to the barrel of the launcher, and in a further embodiment, proximate to the point of projectile exit, and in any event along the launch axis of the projectile. (See FIG. 1, for example). The at least one magnet **500** is preferably magnetically-aligned with the launch axis. In a further embodiment, a launcher accessory **1100** comprises at least one permanent magnet **1500** (see FIG. 7, for example). The launcher accessory may be removably attachable to a launcher **1000**, and the at least one magnet **1500** of the accessory may be disposed along the launch axis of the projectile that is to be launched by the launcher.

In an embodiment, and as shown in an exemplary embodiment in FIG. 6, the projectile comprises at least one coil of wire **550**. When the projectile is launched, the at least one magnet **500** of the launcher and/or the at least one magnet **1500** of the launcher accessory **1100** causes a rapid change in magnetic flux of coil **550** of the moving projectile. This rapid change causes a current to be induced through the coil **550** of the projectile, causing an inductive energy to be produced. The resultant energy can be used to cause an initiator (described elsewhere herein) to be activated, for example. That is, electrical energy can be generated in this embodiment from the change in magnetic flux as the projectile moves through the magnetic field caused by the at least one magnet **500** and/or **1500**.

An exemplary launcher **1000** is shown in FIG. 1A. The launcher comprises a barrel **1010** for directing and launching a projectile **100**. The launcher **1000** may also comprise a chamber **1015** for holding a projectile prior to firing thereof. It will be apparent that the launcher **1000** shown in FIG. 1a may be in other configurations so long as the launcher **1000** is capable of firing a projectile **100** of the projectiles disclosed herein.

In an embodiment, the projectile **100** housing opens or otherwise separates (as shown in FIG. 2 as **100a** and **100b**) after it leaves the barrel **1010** of a launcher **1000** to distribute a payload. That is, the rupturing or breaching of the projec-

tile housing or the separation of housing components creates an opening in the projectile **100** out of which the payload **200** may emanate.

As shown in FIG. 3, the launcher and projectile system **5** may comprise a magazine **1040** that holds a plurality of projectiles **100** and that feeds said projectiles **100** to the launcher **1000** for firing/launching the projectiles **100**.

In an embodiment, and as shown in FIG. 4, the initiator **150** may be an electric match, which electric match may heat **10** upon activation to create an opening in the shell of the projectile **100** to release the payload **200**. It will be apparent that the initiator may be activated by the at least one magnet **500** of the launcher and/or the at least one magnet **1500** of the launcher accessory. In said embodiment, the initiator will **15** initiate opening of the projectile immediately or shortly after exiting the launcher. This would be desirable in a short-range situation, for example.

In another embodiment, the initiator **150** comprises a resistive heating element, which may element becomes heated upon receiving energy from the coil **550** of wire of the projectile **100**. The element, in its heated state, preferably causes the shell of the projectile **100** to degrade and rupture to release the payload.

In another embodiment, the initiator **150** comprises a nichrome wire coupled with a mechanical energy storage means (such as a spring). In this configuration, the mechanical energy storage means may be disposed within the projectile **100** such that it is biased against the shell **102**. When the projectile is launched, the energy from the coil **550** **20** of wire (generated by the movement of the projectile **150** through the magnetic field caused by the at least one magnet **500** and/or **1500**) may cause the nichrome wire to heat such that the heat may cause the shell **102** to weaken and/or melt. In the weakened state, the potential energy of the mechanical energy storage may be converted to kinetic energy to cause the weakened shell **102** to rupture such that the payload is **25** released.

In an embodiment, activation of the initiator **150** does not occur until the projectile **100** reaches a threshold velocity. In **40** an embodiment, the threshold velocity is between 50 and 300 feet per second. In such an embodiment, the initiator is configured not to activate until a threshold minimum current is reached. As the induced voltage in a coil of wire **550** is directly proportional to change in magnetic flux divided by **45** the change in time, if the change in time is lower (i.e. the projectile **100** passes through the magnetic field lines of the permanent magnet at a higher velocity), a higher voltage in the projectile coil **550** will be induced and hence a higher current will be moved through the coil **550** to the initiator **150**. Therefore, the projectile **100** must be traveling with sufficient threshold velocity to induce this threshold current **50** value for activation of the initiator **150**.

In another embodiment, and as shown in FIG. 5, the projectile **100** may comprise a ram **108**. The ram **108** is **55** movable within the housing of the projectile such that when the initiator **150** (such as an electric match) activates, the ram **108** is moved by the force activation. In an embodiment, the ram **108** is proximate to a portion of the interior of the shell **102** such that the movement of the ram **108** caused by **60** the initiator contacts and causes the shell to separate, rupture, open, etc. such that the payload may be released from the shell. In such an embodiment, the payload may also be proximate to the region of the shell **102** that is contacted by the ram **108** and/or that is opened by the ram **108**. An exemplary opening of the projectile is shown in FIG. 5 in **65** which a moving projectile **100** has disrupted the static field lines **501** (being generated by a magnetic element/s **500**) to

activate the initiator 150, which accelerates the ram 108, such that the end cap 104 is ejected, and the payload 200 is thereafter dispersed. Stoppers 109 may be provided to ensure that the ram 108 does not eject with the payload 200 and end cap 104.

Referring now to FIG. 7, a launcher accessory 1100 for a launcher is shown. The launcher accessory 1100 comprises at least one magnet 1500. The launcher accessory 1100 may be removably attached to a launcher (including, but not necessarily limited to launcher 1000). The accessory 1100 is preferably attached to a launcher such that the at least one magnet 1500 of the accessory 1100 is disposed in sufficient proximity to the launch axis of the launcher to facilitate launch of the projectile 100 and to engage the coil of wire 550 of the projectile 100 prior to or coincident with launch of the projectile. FIG. 7 also shows exemplary magnetic flux lines 1501 through which a projectile may pass and which may engage the coil of wire 550 of the projectile. In this exemplary embodiment, the magnetic flux 1501 is disposed along the launch axis of the accessory 1100 and is accordingly magnetically aligned with path of the projectile's launch. In an embodiment, the accessory 1100 is an elongated cylinder in shape, with a circumference that corresponds to the circumference of the barrel of the launcher to which the accessory 1100 is attached. Attachment of the accessory 1100 to the launcher 1000 may be by way of complementary engagement features, by a friction- or press-fit engagement, or by threaded connection, for example.

As shown in FIG. 7, the launcher 1000 may comprise a trigger 1080 to initiate the launch process. It will be apparent that the activation of the initiator by the launcher and/or launcher accessory eliminates the requirement that the projectile comprise a self-contained power source (i.e., a battery for the projectile is not required), thereby eliminating the possibility that the projectile will suffer a power drain prior to launch.

FIG. 1 represents a projectile launcher 1000 that is preferably based on electrical-driven or a combination of electrical and combustion or compressed gas means. It is understood that the projectile is not limited to a particular launching method. In an embodiment, the projectile herein is of lightweight construction (for at least the reason that it does not require an internal battery), such that compressed gas can sufficiently and effectively launch the projectile. However, the disclosure may, in other embodiments include, a primer and/or propellant on the projectile and a hammer of the launcher to strike such primer, as well as other means of launching the projectile other than by way of compressed gas.

The projectile, launcher, and launcher accessory disclosed herein offer the advantages of more controlled release of payload than existing solutions can offer. The projectile further does not require impact upon a target. Configuration of the shell of the projectile disclosed herein may also increase accuracy of flight of the projectile to further improve the safety of use of the projectile disclosed herein. Furthermore, the projectile can be kept in an unarmed state until the projectile is launched from the launcher.

The foregoing descriptions of specific embodiments of the present disclosure have been presented for purposes of illustration and description. They are not intended to be exhaustive or to limit the present disclosure to the precise

forms disclosed, and obviously many modifications and variations are possible in light of the above teaching. The exemplary embodiment was chosen and described in order to best explain the principles of the present disclosure and its practical application, to thereby enable others skilled in the art to best utilize the disclosure and various embodiments with various modifications as are suited to the particular use contemplated.

What is claimed is:

1. A projectile and launcher system,
said launcher comprising a launch axis and at least one permanent magnet,

said projectile comprising a housing, a payload, a conductive wire coil, a moveable ram and an initiator,
wherein said at least one permanent magnet is magnetically aligned with said launch axis such that it induces a current in the conductive wire coil of the projectile during launch of said projectile,
wherein said initiator is activated by said current,
and wherein said activated initiator causes said projectile

housing to rupture, disintegrate, separate or otherwise have an opening created therein after launch and release said payload.

2. The system of claim 1, wherein said initiator consists of at least one of an electric match, a nichrome wire operatively coupled to a spring, and a resistive heating element.

3. The system of claim 1, wherein said activation of said initiator does not occur unless the velocity of said projectile reaches a threshold level.

4. An accessory for a launcher for removable attachment to a projectile launcher of a projectile, which projectile comprises a coil of wire, an initiator, a moveable ram, and a payload,

said accessory for a launcher capable of removable attachment with said launcher,
said launcher comprising a launch axis,

said accessory for a launcher comprising a launch axis,
and at least one permanent magnet,
wherein said launch axis of said accessory for a launcher is physically aligned with said launch axis of said launcher to facilitate launch of the projectile,

wherein said at least one permanent magnet of said accessory for a launcher is magnetically aligned with said launch axis of said launcher such that said magnet may induce a current in the conductive wire coil of the projectile during launch of said projectile,
wherein said initiator of said projectile is activated by said current,

and wherein said activated initiator causes said projectile housing to rupture, disintegrate, separate or otherwise have an opening created therein after launch and release a payload.

5. The accessory of claim 4, wherein said initiator consists of at least one of an electric match, a nichrome wire operatively coupled to a spring, and a resistive heating element.

6. The accessory of claim 4, wherein said activation of said initiator does not occur unless the velocity of said projectile reaches a threshold level.
